UNITED STATES PATENT OFFICE.

ALBERT MUDGE FOWLER, OF LOS ANGELES, CALIFORNIA.

ICE-MAKING APPARATUS.

1,301,550.

Specification of Letters Patent. Patented Apr. 22, 1919.

Application filed March 21, 1918. Serial No. 223,728.

To all whom it may concern:

Be it known that I, ALBERT MUDGE FOWLER, a citizen of the United States, and a resident of Los Angeles, in the county of 5 Los Angeles and State of California, have made certain new and useful Improvements in Ice-Making Apparatus, of which the following is a specification.

My present invention relates generally to 10 ice making apparatus, and more particularly to means utilized in connection with ice forming cans and other containers, whereby to agitate the fluid contents of the can during the freezing operation, in order that clear, 15 clean ice may be formed from raw or undistilled water, my object being the provision of a novel and simple arrangement which will avoid the bulky attachments now in use requiring constant attendance, and 20 which will bring about more satisfactory and effective results.

In the manufacture of can ice from raw or undistilled water, the method usually employed is to agitate the water in the cans by 25 means of an air tube extending well toward the bottom of the can and attached at the top to a system of air distributing pipes by a short length of rubber tubing and the like.

Air is supplied to these pipes at a pressure 30 of from three to five pounds per square inch, and the air bubbles rising to the top of the water have a tendency to cause more or less violent agitation of the water being frozen with the result that the face of the 35 ice as it forms, freezing from the outside toward the center will be freed from air bubbles, impurities, matters held in suspension, and the like, concentrating these undesirable particles into a core at the center of the 40 cake, which is drawn out when the cake is nearly frozen, the cavity being then filled with clean and generally distilled water, so that when it is frozen, the result will be a cake of clear, merchantable ice.

There are a number of objections to this 45 method, one of which is the liability of the tubes freezing into the ice cake and another is the amount of labor the usual method requires and the constant watchfulness necessary to adjust and remove the pipes at the 50 proper times. The chief objection, however, is that after the core is drawn and the cavity refilled, it is impossible to agitate the water with which the cavity is filled without attaching another shorter drop pipe, and the 55 result of this is that almost the entire refill

will freeze white, leaving a very large and objectionable white center in the cake.

My invention aims to avoid the use of drop pipes which it is necessary, as above 60 stated to extend almost to the bottom of the can, and to provide for more effective results, as well as for the agitation of what I have above termed as the refill, by the use of an air induced siphon jet, which may be located 65 wholly within the upper central region of the can and need not be withdrawn until the refill is almost completely frozen, which will cause and maintain a constant circulation of the fluid throughout the entire area of the 70 can in its operation.

In the accompanying drawing illustrating my present invention and forming a part of this specification,

Figure 1 is a vertical section through an 75 ice forming can, showing the ice cake partly formed and illustrating the application of my invention thereto;

Fig. 2 is an enlarged vertical section through the upper central portion of the 80 can and through my improved jet member, and,

Fig. 3 is a detail horizontal section taken substantially on line 3—3 of Fig. 2.

Referring now to these figures, I show 85 an ice forming can at 10 in Figs. 1 and 2, the ice forming liquor of which appears at 11, and the partly formed ice cake at 12. The upper end of the can receives a top 13 centrally apertured for the extension of an 90 air supply pipe 14, so that the latter may extend downwardly into the can, the outer end of this pipe connecting by any suitable means, as for instance a flexible tube 15, to any suitable source of compressed air supply. 95 The pipe 14 is adjustably held in connection with the can top 13, by a clamp 16, most plainly seen in Fig. 3, so that the jetting member generally indicated at 17, in Fig. 1, may be projected more or less below 100 the normal level of the fluid within the can, although it is to be noted at this point that the said jetting member is located wholly within the upper central region of the can.

The inner end of the pipe 14 directly connects to and communicates with an air nozzle 18, the latter of which is projected axially and in spaced relation within a tubular casing 19, the upper intake end of which surmounts the lower or inner end of the 110 pipe 14, and is substantially of the bell shape shown in Fig. 2. The lower discharge

end of this casing 19 projects below and beyond the discharge end of the air nozzle 18, so that when the action of the latter fluid is drawn downwardly, through the upper bell shaped open end of the casing 19 and discharged from the lower end of the latter, sufficient air pressure is admitted to the nozzle 18 to bring this action about.

In this way I am enabled to provide a means located wholly in the upper central region of the can for causing a complete circulation of the ice forming fluid throughout the entire can, as indicated by the arrows in Fig. 1, so as to avoid the extension of an air inlet pipe to a point near the bottom of the can, as usual, and at the same time bring about more effective results, particularly in view of the fact that it need only be withdrawn when the refill, as above described, is almost entirely frozen.

In order to heighten the effect of the jet discharge from the lower end of the casing 19, the latter may have internal spirally arranged ribs or vanes, as indicated at 20 in Fig. 2, which will promote a whirling motion to the water and air discharged from the casing.

I claim:—

1. The combination with an ice forming container, of means for causing complete circulation of the fluid within the container consisting of an air and water jetting member located wholly within the upper central region of the tank and having an air supply pipe, an air nozzle connected to the supply pipe, and a casing surrounding the nozzle in fixed spaced relation, the upper end of which casing is enlarged to form a liquid intake, and the lower discharge end of which projects beyond the discharge end of the said air nozzle.

2. The combination with an ice forming container, of means for causing complete

circulation of the fluid within the container consisting of an air and water jetting member located wholly within the upper central region of the tank and having an air supply pipe, an air nozzle connected to the supply pipe, a casing surrounding the nozzle in fixed spaced relation, the upper end of which casing is enlarged to form a liquid intake, and the lower discharge end of which projects beyond the discharge end of the said air nozzle, and is provided with internal means for causing whirling motion of the stream of water and air discharged therefrom.

3. The combination with an ice forming container, of means for causing complete circulation of the fluid within the container consisting of an air and water jetting member located wholly within the upper central region of the tank and having an air supply pipe, an air nozzle connected to the supply pipe, a casing surrounding the nozzle in fixed spaced relation, the upper end of which casing is enlarged to form a liquid intake, and the lower discharge end of which projects beyond the discharge end of the said air nozzle, and is provided with internal spiral vanes, for the purpose described.

4. The combination with an ice forming can having a centrally apertured top, an air supply pipe extending downwardly through the said top, a clamping member engaging the pipe and the can top to adjustably secure the former in connection with the latter, and an air actuated water jetting member at the inner end of the said air pipe, located wholly within the upper central region of the can for the purpose described.

ALBERT MUDGE FOWLER.
